United States Patent Office

Des. 178,881
Patented Oct. 2, 1956

178,881

TIRE

Earle W. Hawkinson, Minneapolis, Minn., assignor to
Paul E. Hawkinson Company, Minneapolis, Minn., a
corporation of Minnesota

Application July 25, 1955, Serial No. 37,115

Term of patent 14 years

(Cl. D90—20)

Fig. 1 is an elevational view of a tire showing my new design; and

Fig. 2 is an enlarged fragmentary sectional view taken on the line 2—2' of Fig. 1.

The side wall portions of my tire are of conventional configuration.

I claim:

The ornamental design for a tire, as shown and described.
